POWER MEAT SAW

Edward C. Karp, Belvidere, Ill., assignor to Sanitary
Scale Company, Belvidere, Ill., a corporation of Illinois

Filed Dec. 9, 1959, Ser. No. 58,622

Term of patent 14 years

(Cl. D55—1)

FIGURE 1 is a perspective view of a power meat saw embodying my new design;

FIGURE 2 is a side elevation showing the access door in open position;

FIGURE 3 is a front elevation;

FIGURE 4 is a rear elevation, and

FIGURE 5 is a section view thereof, taken along the line 5-5 of FIGURE 2.

The dominant features of my new design are shown in solid lines in the drawings. The other side elevation, not shown, is substantially plain.

I claim:

The ornamental design for a power meat saw, substantially as shown and described.
